UNITED STATES PATENT OFFICE.

GEORGE SEEDS, OF NEWTON, IOWA, ASSIGNOR TO NEWTON DISC PLOW COMPANY, OF NEWTON, IOWA, A CORPORATION OF IOWA.

GEARING DEVICE FOR WASHING-MACHINES AND WRINGERS.

1,110,830.

Specification of Letters Patent. Patented Sept. 15, 1914.

Application filed December 5, 1912. Serial No. 735,137.

To all whom it may concern:

Be it known that I, GEORGE SEEDS, a citizen of the United States, residing at Newton, in the county of Jasper and State of Iowa, have invented certain new and useful Improvements in Gearing Devices for Washing-Machines and Wringers, of which the following is a specification.

The object of my invention is to provide a gearing device for washing machines and wringers of simple, durable and inexpensive construction.

A further object is to provide in such a device an upright shaft in gear with a power shaft and provided with a gearing device for operating the wringer shaft in either direction and for operating a third shaft from which the dolly is agitated.

A further object is to provide a bracket designed to be arranged beneath the tub and having horizontal bearings for supporting both ends of the horizontal power shaft and a vertical bearing for supporting and mounting the lower end of the vertical shaft.

A further object is to provide a bracket upon the body of the tub to which the tub cover is hinged, which bracket is provided with bearings for the vertical shaft and also for the horizontal shaft operatively connected with the vertical shaft by which the dolly is agitated.

A further object is to provide in such a device a bracket forming a bearing for the dolly shaft and provided with means for guiding a rack bar and with an extension and a bearing thereon for hinging the cover to the body of the machine.

My invention consists in certain details, in the construction, arrangement and combination of the various parts of the device, whereby the objects contemplated are attained, as hereinafter more fully set forth, pointed out in my claims and illustrated in the accompanying drawings, in which:

Figure 1 shows a side elevation of a washing machine and wringer equipped with my improved gearing device. Fig. 2 shows a top view of same. Fig. 3 shows an end elevation of same taken at right angles to the view shown in Fig. 1, and Fig. 4 shows a perspective view of one of the brackets.

In the accompanying drawings, I have used the reference numeral 10 to indicate the tub body of the washing machine which is supported on legs 11, as shown in Fig. 1. The tub is provided with a cover 12 hinged to the tub in a manner hereinafter to be described. Mounted upon the tub is a wringer 13. Suitably mounted upon the legs 11 of the machine is a bracket 14 having horizontal bearings 15 and 16 in line with each other and provided with a vertical bearing 17. Rotatably mounted in the bearings 15 and 16 is a horizontal shaft 18, on one end of which is a belt pulley 19 designed to be connected with a primary source of power, such as a gasoline engine. It will, of course, be understood that the shaft 18 may be operated from an electric motor, if desired.

Mounted upon the top of the tub body, near one edge thereof, is a bracket 20, having near one end an upwardly extending arm 21. The bracket extends beyond the tub body and is provided with a bearing 22 in line with the bearing 17. The bracket 20 is also provided with upward extensions 23 and 24, forming bearings in line with each other. Formed on the bracket 20 is still another extension 25 designed to be secured to one end of the wringer 13. A vertical shaft 26 is rotatably mounted in the bearings 17 and 22 and is provided at its lower end with a beveled gear 27, which is in mesh with the beveled gear 28 on the shaft 18.

Arranged, at right angles to the vertical shaft 26 is a horizontal shaft 29, rotatably mounted in the bearing 23. On one end of the shaft 29 is a crank wheel 30 formed on which is an extended hub or sleeve 31. The hub or sleeve 31 is rotatably mounted in the bearing 24 and is loosely mounted on the shaft 29. Formed on one end of the hub 31 is a clutch member 32, designed to coact with a clutch 33 which is slidably but non-rotatably mounted on the shaft 29. The clutch 33 is operatively connected with a lever arm 34 which is fixed on the rod 35, slidably mounted in bearings 36 on the hinged cover 12.

Secured to the hinged cover 12 is a bracket

39 having an extension 40 which is pivotally connected with the upper end of the extension 21 on the bracket 20, at a point in line with the center of the shaft 29. On the hinged cover 12 is still another bracket 41 forming a bearing for the dolly shaft 42 and provided with guides 43, for the rack bar 44, which is in mesh with the pinion 45 on the dolly shaft 42. On the tub body is a bracket 46 pivoted to which is a socket 47 having a handle by which the dolly may be manually operated. The socket 47 is operatively connected with the rack bar 44 by means of parallel links 48 which are pivoted at their respective ends to the rack bar and to the socket 47. The rack bar is also pivoted to a link 49, which is in turn pivoted off center to the crank wheel 30. On one end of the shaft 29 is a beveled gear 51 which is in mesh with a beveled gear 52 on the vertical shaft 26.

The portion 25 of the bracket 20 is formed with an outward extension 50, forming a bearing for the shaft 26 in line with the bearing 22. Mounted on the shaft 26, above the bearing 50 is a beveled gear 53, formed on which is a clutch member 54. Mounted on the shaft 26, above the beveled gear 53 and spaced apart therefrom, is a beveled gear 55, formed on which is a clutch 56. Slidably, but non-rotatably mounted on the shaft 26, between the gears 53 and 55, is a double faced clutch member 57 operatively connected with which is a shifting arm 58 which is connected with a rod 59. The lower end of the rod 59 is pivoted to a link 60 which in turn is pivoted to a horizontally mounted rod 61, on one end of which is a handle 62. The beveled gears 53 and 55 are in mesh with a beveled gear 63 on the end of one of the wringer shafts 64.

The hinged cover 12 is pivoted to the extension 21 of the bracket 20 at a point in line with the center of the shaft 29. The hub 31 of the crank wheel 30 is rotatably mounted on the shaft 29 and an extension 65 on the bracket 41 forms a bearing in which the hub 31 is journaled, thereby hinging the cover 12 to the shaft 29. On account of the manner in which the cover 12 is hinged to the tub body at points in line with the center of the shaft 29, it does not interfere with the rack bar 44 when the hinged cover is raised, and I thereby avoid breaking any of the parts should the hinged cover be raised when the dolly is being operated.

The parts hereinbefore described are so constructed and arranged that their practical operation is as follows: When power is applied to the pulley 19 and the shaft 18 is thereby operated, the shaft 26 is rotated. The beveled gears 52 and 51 being always in mesh, the shaft 29 will be rotated with the shaft 18. The crank wheel 30, however, is

only rotated when the clutch member on the hub 31 is in mesh with the clutch member 54. The beveled gear wheels 53 and 55 are always in mesh with the wheels 63 but the beveled gears 53 and 55 are loosely mounted on the shaft 26. The clutch 57 is so mounted that it may be held in neutral position or may be thrown into gear with either of the beveled gears 53 or 55, thereby turning the wringer shaft in either direction. It thus appears that the wringer shaft may be operated in either direction and at the same time the dolly may be operated or not, as may be desired. The gears from which the wringer shaft is operated, and from which the shaft 29 is operated, are all in line upon the same shaft, whereby I secure a very simple and strong construction.

Special attention is called to the advantages of my improved brackets. The bracket 20 is formed with bearings whereby the shafts 29 and 26 are always held true and in proper adjustment with relation to each other. The bracket 14 forms both a support and a bearing for the shaft 26 and is such that the shafts 26 and 18 are always held in proper position with relation to each other. The construction of my gearing and brackets is simple and durable and a suitable casting may be readily provided for the gears 51, 52, 53, 55 and 57.

I claim as my invention:

1. In a device of the class described, the combination of a support, a hinged member thereon, a bracket provided with horizontal bearings in line with each other and with an extension, one end of which is in line with said horizontal bearings, with an extension designed to form a support, with vertical bearings in line with each other, a bracket on said hinged member having an extension pivoted to the extension on said first bracket in line with said horizontal bearings, a second bracket on said hinged member forming a vertical bearing and provided with guides for a rack bar, said second bracket on said hinged member being provided with an extension forming a bearing in line with the horizontal bearings on said first bracket.

2. In a device of the class described, the combination of a support, a hinged member thereon, a bracket on said support, said bracket having formed thereon horizontal bearings in line with each other and having an extension, one end of which is in line with said horizontal bearings, a shaft mounted in said horizontal bearings, a crank wheel having an extended hub formed thereon loosely mounted on said horizontal shaft, a vertical shaft mounted on said support, a beveled gear on said vertical shaft, a beveled gear on said horizontal shaft in mesh with said first beveled gear, a bracket on said hinged member pivoted to the extension on said first bracket, in line with said horizontal bear-

ings, a second bracket on said hinged member, said last named bracket being provided with guides having a rack bar and with an extension forming a bearing for said hub, a 5 rack bar slidably mounted in said guides, a link pivoted to said rack bar and to said crank wheel, and a clutch member mounted on said second horizontal shaft, slidably but

non rotatably and designed to coact with the clutch member on said hub.

Des Moines, Iowa, November 22, 1912.

GEORGE SEEDS.
